DESIGN FOR A DRESS ENSEMBLE

Philip Wenett, New York, N. Y.

Application January 28, 1937, Serial No. 67,310

Term of patent 3½ years

To all whom it may concern:

Be it known that I, Philip Wenett, a citizen of the United States of America, residing in New York city, in the Borough of Manhattan, county and State of New York, have invented a new, original, and ornamental Design for a Dress Ensemble, of which the following is a specification, reference being had to the accompanying drawing, forming part thereof, wherein,

The design is characterized by the combination on the dress, as shown, of the superimposed floral appliqued motifs arranged as shown.

The rear portion of the jacket is conventional.

I claim:

The ornamental design for a dress ensemble, substantially as shown and described.

PHILIP WENETT.
